UNITED STATES PATENT OFFICE.

CHARLES D. ORCUTT, OF NORTH TONAWANDA, NEW YORK, ASSIGNOR TO BUFFALO SLED COMPANY, OF BUFFALO, NEW YORK.

SHOVEL.

990,898.

Specification of Letters Patent.

Patented May 2, 1911.

Application filed October 20, 1910. Serial No. 588,067.

To all whom it may concern:

Be it known that I, CHARLES D. ORCUTT, a citizen of the United States, residing at North Tonawanda, in the county of Niagara and State of New York, have invented new and useful Improvements in Shovels, of which the following is a specification.

The object of this invention is the production of a shovel which is more particularly designed for handling snow and which is not only stronger and lighter than shovels of the same capacity heretofore in use but which permits of detaching the handle from the blade, so that a consignment of shovels can be shipped in a knock down condition at lower rates and the handles can also be readily replaced by new ones, thereby saving the blades instead of discarding the same with the broken handles as has been customary heretofore.

In the accompanying drawings: Figure 1 is a rear elevation of a snow shovel embodying my improvements. Fig. 2 is a longitudinal section of the same in line 2—2, Fig. 1. Fig. 3 is a plan view of a blank from which two of the blade stiffening ribs are produced. Fig. 4 is a side view of one of said ribs in a partially formed condition.

Similar letters of reference indicate corresponding parts throughout the several views.

A represents the blade of the shovel which is constructed of sheet metal and curved vertically in the form of a scoop in a well known manner. At its front edge the blade is provided with the usual wedge strip *a* which is secured thereto by riveting, as shown, or by any other suitable means.

B represents the handle which is preferably constructed of wood and detachably connected with the blade in a manner to be presently described.

On its underside the blade has secured thereto two ribs which serve the double purpose of stiffening the blade and also as part of the means for connecting the handle with the blade. Each of these ribs is constructed of angle iron and comprises an inner laterally projecting flange *C* which is secured to the rear side of the blade by rivets *c* so as to be arranged parallel with the plane of the same and an outer flange *D* which projects rearwardly from the inner flange and at right angles to the same. Each of these

ribs is bent laterally near its upper end and the two ribs are so arranged on the rear side of the blade that the front parts *e* thereof converge upwardly while the upper parts *e¹* thereof are parallel and are separated by an intervening space. The front parts *e* of the ribs are curved to fit the back of the blade and the front ends thereof are arranged between the blade and the adjacent part of the wearing strip. The inner flange of each rib is preferably rectangular or of the same width throughout its length while the outer flange tapers from its upper end toward its lower end. By this means the shovel can be brought close to the surface from which the snow is being removed and the stiffening effect of the same is gradually increased from the front edge to the rear edge of the blade, thereby strengthening the different parts of the blade in proportion to the load or strain to which the same is subjected while in use. A coöperating pair of such ribs are preferably constructed from a rectangular blank of sheet metal, as shown in Fig. 3. This blank is divided obliquely in the direction of its length on the full line *f* and then the sections are folded on the dotted lines *g* which are arranged parallel to the outer longitudinal edges of the blank, thereby forming two ribs each having an inner rectangular flange and an outer triangular flange. After the ribs have been thus cut and folded the same are bent so that the front parts converge upwardly and the rear parts are parallel when applied to the blade and the front parts are also curved to fit the shape of the blade.

The handle is arranged at its lower end between the parallel upper parts of the ribs and is preferably detachably secured thereto by bolts *h* passing transversely through to the handle and the adjacent parallel parts of the outer flanges.

When shipping the shovels in quantities the handles are removed from the blades, thereby permitting the same to be stowed more compactly and reducing cost of transportation. Furthermore by making the handle detachable from the blade a new handle can be readily substituted for a broken one, thereby avoiding the necessity of discarding the entire shovel as frequently occurs when the handle of a shovel as now constructed is broken.

I claim as my invention:

1. A shovel comprising a blade, two ribs secured to the rear side of the blade and converging upwardly, each rib having an inner flange arranged parallel with the plane of the blade and secured to the blade and an outer flange arranged at right angles to the inner flange, said outer flange tapering from its upper end toward its lower end and said inner flange being of the same width throughout its length, and a handle arranged between the upper ends of the ribs and secured to the outer flanges thereof.
2. A shovel comprising a blade, two ribs arranged on the rear side of the blade and having their lower parts converging up-

wardly and their upper parts arranged parallel, each rib being of angular form and having an inner flange which is secured to the blade and is of the same width throughout its length and an outer flange which tapers from its upper end toward its lower end, a handle arranged between the parallel parts of said ribs, and bolts passing through said handle and the outer flanges of the ribs.
